(57) **CLAIM**

The ornamental design for a truck body roof top with a dynamic aspect in the roof top, as shown and described.

DESCRIPTION

FIG. 1 is a dynamically fully closed upper-right perspective view illustrating our ornamental design for a truck body roof top with a dynamic aspect in the roof top;

FIG. 2 is a dynamically partially opened upper-right perspective view thereof;

FIG. 3 is a further dynamically partially opened upper-right perspective view thereof;

FIG. 4 is a further dynamically partially opened upper-right perspective view thereof;

FIG. 5 is a further dynamically partially opened upper-right perspective view thereof;

FIG. 6 is a further dynamically fully opened upper-right perspective view thereof;

FIG. 7 is a dynamically partially closed upper-right perspective view thereof;

FIG. 8 is a further dynamically partially closed upper-right perspective view thereof;

FIG. 9 is a further dynamically partially closed upper-right perspective view thereof;

FIG. 10 is a further dynamically partially closed upper-right perspective view thereof;

FIG. 11 is a further dynamically fully closed upper-right perspective view thereof;

FIG. 12 is a dynamically partially opened upper-left perspective view thereof;

FIG. 13 is a further dynamically partially opened upper-left perspective view thereof;

FIG. 14 is a further dynamically partially opened upper-left perspective view thereof;

FIG. 15 is a further dynamically fully opened upper-left perspective view thereof;

FIG. 16 is a dynamically partially closed upper-left perspective view thereof;

FIG. 17 is a further dynamically partially closed upper-left perspective view thereof;

(Continued)

FIG. 18 is a further dynamically partially closed upper-left perspective view thereof; and,
 FIG. 19 is a further dynamically fully closed upper-left perspective view thereof.
 In the drawings, the broken lines depict environmental subject matter only and form no part of the claimed design. The appearance of the dynamic images sequentially transitions between the images shown in FIGS. 1-19. The process or period in which one dynamic image transitions to another in FIGS. 1-19 forms no part of the claimed design.
